DUAL SCRIBER

Leo J. Reno, Flint, Mich.

Application April 26, 1956, Serial No. 580,802

4 Claims. (Cl. 33—41)

This invention relates to measuring and marking devices and more particularly pertains to a dual scribing or marking device which is capable of easily scribing surfaces which are otherwise extremely difficult to scribe by using a reference point or line on an easily accessible surface.

Scribing and marking devices have been employed heretofore to facilitate accurately scribing in drafting, drawing, machining, and milling; however, the several devices of the prior art have not proven entirely satisfactory inasmuch as they are complicated in design and construction, expensive to manufacture, difficult to use, and are not readily adaptable for marking substantially unseeable surfaces.

With the foregoing in view, the primary object of the invention is to provide a marking or scribing device which is simple in design and construction, inexpensive to manufacture, easy to use, and easy to mark otherwise difficult and unseeable surfaces.

An object of the invention is to provide a protractor base having a scale slidably and rotatably attached thereto which is fixable in an adjustable position.

An object of the invention is to provide dual scribing devices which are linearly and transversely adjustable relative to the scale and which have pivoted feet for the purposes of angularly moving the scribe points attached thereto.

An object of the invention is to provide a center slide between the dual slides for providing an anchor for an adjusting nut and screw secured to one dual scribe for fine adjustment.

These and other objects of the invention will become apparent by reference to the following description of a dual scribing device embodying the invention taken in connection with the accompanying drawing in which:

Fig. 1 is a top plan view of a portion of the slide and scale area of the device.

Fig. 2 is a side elevational view of the device seen in Fig. 1.

Fig. 3 is a cross-sectional view of Fig. 1 taken on line 3—3 thereof.

Fig. 4 is a side elevational view of the device seen in Figs. 1—3 in conjunction with a protractor base and shown in relation to scribing surfaces on a workpiece.

Fig. 5 is a view similar to Fig. 4 showing the device in reverse condition; and

Fig. 6 is a rear elevational view of the scribe foot showing the indices and handle.

Referring now to the drawing, wherein like numerals refer to like and corresponding parts throughout the several views, the scribing and marking device disclosed therein comprises a scale 10 having dual scribes 11 and 12 slidably mounted thereon, a base and protractor 13 for angularly and slidably adjusting and positioning the scale 10, a centering fine adjustment slide 14 mounted on the scale 10 and attached to the one dual scribe as by the adjusting element 15.

2

More particularly, the protractor base comprises a base 20 for standing on a floor 21 or a block 22 and a protractor element 23 having an annular recess 24 housing the block 25 which not only grips the protractor element 23 but which also includes the slide 10, and the block 25 and the set screw 26 are capable of holding the protractor element 23 and the scale 10 in any linearly or angularly adjusted position. The block 25 has bifurcated extending ends which include both the element 23 and the scale 10 so that by tightening the jamming set screw 26, the members are frictionally engaged to prevent relative movement in an adjusted position. The block 25 is clamped to the protractor 13 by a screw whose axis is radial to the protractor plate 23 as shown in the U. S. patent to Murdock et al. No. 793,602.

The dual scribe elements 11 and 12 comprise slide blocks 30 each having a central longitudinal opening 31 for slidably receiving the scale 10, a spring 32 disposed between the block 30 and the scale 10 to provide frictional engagement therebetween to prevent inadvertent sliding of the block 30 on the scale 10, and a thumb screw 33 adapted to bear against the spring 32 whereas to force the spring 32 against the scale 10 and thereby lock the block 30 relative to the scale 10 in any adjusted linear position. The face of each block 30 is provided with walls 34 and 35 providing a transverse slideway 36 and a transverse slide 37 is slidably disposed in each slideway 36 and is equipped with a slot 38 which fits over the stud 39 and the thumb nut 40 is adapted to engage the transverse slide 37 in fixed adjusted relationship to the slide block 30. The scribe feet 41 are pivotally mounted on the bottom of the transverse slides 37 as by the bolts 42 and they carry the scribe points 43.

The center slide disposed between the dual slides 11 and 12 comprises a slide block 50 slidably mounted on the scale 10 and a friction spring 51 and thumb screw 52 adapted to provide frictional and fixed engagement respectively between the slide block 50 and the scale 10; the block 50 is equipped with a yoke having dual arms 53 and 54 which have apertures for receiving the bolt 55 therethrough which is attached to the boss 56 mounted on one of the dual slides 30, and a thumb nut 57 disposed on the bolt 55; it can be seen that by anchoring the slide 50 via the thumb screw 52 and manipulating the nut 57 that the slide block 11 attached to the bolt 55 can be finely adjusted with precision.

The protractor is provided with a scale 60 for adjusting the angular position of the scale 10 relative thereto; the scale is also equipped with markings 62 for adjusting the scribe elements 11 and 12 linearly thereof; the slide blocks 30 are provided with a scale 64 for transversely adjusting the transverse slide blocks 37 relative thereto; and the feet 41 are provided with a scale 63 and a handle 74 for adjusting the feet angularly of the transverse slide bar or element 37.

In use or operation, the protractor base 20 is set on a floor 21 or block 22 and a known mark such as 80 is finely adjusted to the one scribe point 43 and then the other scribe point is brought into position so as to mark the workpiece 81 with a mark 82 as seen in Fig. 4.

Fig. 5 illustrates the use of the device in conjunction with an easily seen mark 83 and it is to be noted that the difficultly seen mark 84 is easily placed on a workpiece 85 by the other scribe element.

The inventive marking device with these features constitutes a compact, durable, neat appearing mechanism, easily operated to locate difficult marks relative to easily seeable marks as will be appreciated by those skilled in the art.

Although but a single embodiment of the invention has been shown and described in detail, it is obvious that many

changes may be made in the size, shape, detail, and arrangement of the various elements of the invention within the scope of the appended claims.

I claim:

1. A dual scribe for easily marking otherwise very difficult surfaces comprising a base having a protractor element, a scale rotatably and slidably mounted relative to said base and fixable in any adjusted linear and angular position, oppositely disposed dual slides slidably disposed on said scale, springs disposed between said slides and said scale establishing a displaceable frictional engagement between said slides and said scale, thumb screws on said slides adapted to fix said slides relative to said scale in any adjusted position, walls on each said slide defining a slideway at a right angle to said scale, a stud in each said slideway, cross slides disposed in said slideways each having a slot for receiving said stud, thumb nuts on said studs adapted to secure said cross-slides relative to said slide in any adjusted position, feet pivotally mounted on said cross-slides, screws securing said feet relative to said cross-slides in any adjusted angular position, scribe points on said feet, a center slide on said scale between said dual slides, a friction spring between said center slide and said scale, a thumb screw on said center slide for fixing said center slide relative to said scale, an apertured yoke on said center slide, a boss on one of said dual slides, a bolt fixed on said boss disposed in said yoke apertures, and a thrust nut disposed in said yoke on said bolt so as to be capable of moving said dual slide attached to said bolt for fine adjustment purposes with said center slide providing an anchor therefore; said protractor base, said scale, said cross-slides, and said feet being provided with indices and graduation marks for determining adjusted positions.

2. A dual scribe for easily marking otherwise very difficult surfaces comprising a scale, oppositely disposed dual slides slidably disposed on said scale, springs disposed between said slides and said scale establishing a displaceable frictional engagement between said slides and said scale, thumb screws on said slides adapted to fix said slides relative to said scale in any adjusted position, walls on each said slide defining a slideway at a right angle to said scale, a stud in each said slideway, cross slides disposed in said slideways each having a slot for receiving said stud, thumb nuts on said studs adapted to secure said cross-slides relative to said slide in any adjusted position, feet pivotally mounted on said cross-slides, screws securing said feet relative to said cross-slides in any adjusted angular position, scribe points on said feet, a center slide on said scale between said dual slides, a friction spring between said center slide and said scale, a thumb screw on said center slide for fixing said center slide relative to said scale, an apertured yoke on said center slide, a boss on one of said dual slides, a bolt fixed on said boss disposed in said yoke apertures, and a thrust nut disposed in said yoke on said bolt so as to be capable of moving said dual slide attached to said bolt for fine adjustment purposes with said center slide providing an anchor there-

fore; said scale, said cross-slides, and said feet being provided with indices and graduation marks for determining adjusted positions.

3. A dual scribe for easily marking otherwise very difficult surfaces comprising a scale, oppositely disposed dual slides slidably disposed on said scale, springs disposed between said slides and said scale establishing a displaceable frictional engagement between said slides and said scale, thumb screws on said slides adapted to fix said slides relative to said scale in any adjusted position, walls on each said slide defining a slideway at a right angle to said scale, a stud in each said slideway, cross slides disposed in said slideway having a slot for receiving said stud, thumb nuts on said studs adapted to secure said cross-slides relative to said slide in any adjusted position, scribe points on said cross-slides, said scale and said cross-slides being provided with indices and graduation marks for determining adjusted positions; said scribe points being oppositely disposed for scribing opposed surfaces at the same time.

4. A dual scribe for easily marking otherwise very difficult surfaces comprising a scale, oppositely disposed dual slides slidably disposed on said scale, thumb screws on said slides adapted to contact said scale to fix said slides relative to said scale in any adjusted position, walls on each said slide defining a slideway at a right angle to said scale, a stud in each said slideway, cross slides disposed in said slideway having a slot for receiving said stud, thumb nuts on said studs adapted to secure said cross-slides relative to said slide in any adjusted position, feet pivotally mounted on said cross-slides, screws securing said feet relative to said cross-slides in any adjusted angular position, scribe points on said feet, a center slide on said scale between said dual slides, a thumb screw on said center slide for fixing said center slide relative to said scale, an apertured yoke on said center slide, a boss on one of said dual slides, a bolt fixed on said boss disposed in said yoke apertures, and a thrust nut disposed in said yoke on said bolt so as to be capable of moving said dual slide attached to said bolt for fine adjustment purposes with said center slide providing an anchor therefore; said scale, said cross-slides, and said feet being provided with indices and graduation marks for determining adjusted positions.
